UNITED STATES PATENT OFFICE.

WILLIAM GEIPEL, OF SOUTHWARK, ENGLAND.

STEAM-TRAP.

No. 846,300.

Specification of Letters Patent.

Patented March 5, 1907.

Application filed July 12, 1906. Serial No. 325,859.

To all whom it may concern:

Be it known that I, WILLIAM GEIPEL, a subject of the King of Great Britain and Ireland, residing at Southwark, in the county of London, England, have invented Improvements in or Relating to Steam-Traps, of which the following is a specification.

It is found in expansion steam-traps of the type described in my former patent specification, No. 560,491, dated May 19, 1896, and comprising two expansion-tubes rigidly fixed at one end to the trap frame or body and free to move laterally at their other ends and which are connected together by a valve-body containing a valve controlling the passage of fluid from one tube to the other, that inasmuch as the valve is closed against the pressure of steam it is necessary to limit the area of the discharge-opening controlled by the valve; otherwise the force available for keeping it closed would be counterbalanced by the pressure of the steam acting over the area of the valve, and in any case in traps of the type referred to there is a period—namely, just before the opening of the valve, when the expansion parts of the trap are partly contracted—when the force available to keep the valve closed is practically balanced by the pressure of steam upon the valve, and during this period there is a tendency for water or steam to leak past the valve.

When water or steam passes between two adjacent faces, such as those of the valve and its seat, there is a tendency to cutting or wearing away of the metal faces, more especially in the case of steam-traps, which frequently have to discharge water containing sediment or impurities which may act upon the said faces either mechanically or chemically, or both.

In expansion steam-traps of a different type to that described in my said former specification the water-discharge valve has, in order to avoid the disadvantage above mentioned, been arranged on the inlet side of the water-discharge opening, so as to open in an inward direction against the fluid-pressure within the trap, and has been disconnected from the means used for directly opening it, so that upon being opened to a sufficient extent to permit water to leak past it it will be immediately moved into its fully-open position by the wedging action of the escaping water, and thus allow of free and rapid discharge of water, and will afterward

be moved into its closed position by the fluid-pressure within the trap, aided, it may be, by a spring, when the expansion portion of the trap again expands upon the admission of steam thereto.

Heretofore there have been difficulties in the way of successfully applying such valves to expansion steam-traps of the type described in my said former specification and known as "Geipel" steam-traps, and the present invention has reference to improvements in or relating to traps of this type, whereby valves arranged and operating in the manner above described can be successfully and advantageously applied to such traps. For this purpose in place of the valve arrangement described in my said prior specification, wherein the valve is arranged outside the water-discharge opening and is closed against the steam-pressure in the trap, the valve-case that connects the free ends of the two expansion-tubes of the trap is so constructed and arranged in relation to the tubes and to the hand-lever provided for opening the valve by hand, when desired, that the valve will be located at the inner side of the water-discharge opening, so that it will be closed by the steam-pressure and will be opened against such pressure by the contraction of the expansion-tubes. In this arrangement it is necessary that the contraction of the expansion-tubes should move the valve-spindle against the hand-lever—that is to say, in an opposite direction to that in which it is moved by the expansion-tubes in the trap described in my said prior specification—for which reason the expansion-tube that serves as the inlet-tube is arranged at the top of the trap and the other or outlet-tube at the bottom thereof, or, in other words, that the inlet-tube shall be nearest the lever against which the valve abuts and the outlet-tube farthest therefrom.

To prevent chattering action which is liable to be set up in the valve in the new construction at the time when it is being opened or closed and which would act to destroy the valve face and seat and also to prevent the vibration that is liable to be set up in the trap itself, owing partly to the chattering action of the valve and partly to the rapidity of the discharge through the large discharge-opening employed, and also to prevent the noise and consequent inconvenience caused by so rapid and forcible a discharge, means are provided for throttling the dis-

charge of water at a point between the valve-opening and the outlet end of the discharge-pipe. Such throttling means by reducing the velocity of discharge of water past the 5 valve-seat, especially at high pressures, serves also to transfer wear, due to the issuing water, from the valve-seat to the throttling-point, where wear is of less consequence.

The throttling device employed is so constructed as to be automatic in action and to produce a greater throttling action at high pressure than at low pressure. For this purpose it may conveniently comprise a spring-controlled throttling-gate adapted to be operated by the pressure of the water or steam after the same has passed the valve, the spring acting in such a way that at low pressure the gate will be maintained in a position to provide a maximum opening, so as to produce the minimum throttling effect, and at 20 high pressures the gate will be moved into a position to reduce the opening to its minimum size and produce the maximum throttling effect. This automatic and variable 25 throttling device may be arranged close or adjacent to the valve or it may be placed at a distance therefrom.

In the accompanying illustrative drawings, Figure 1 shows, partly in side elevation 30 and partly in vertical section, a steam-trap of the Geipel type embodying the present invention. Fig. 2 shows in longitudinal vertical section the valve-case which connects the movable free ends of the inlet and outlet 35 expansion-tubes of the trap and is designed for use with a valve arranged to act in the manner hereinbefore described. Figs. 3 and 4 are sections of the valve-case, taken on the lines A A and B B, respectively, of Fig. 2. 40 Fig. 5 shows the valve-case partly in end elevation and partly in cross-section on the line C C of Fig. 2. Figs. 6 and 7 are detail sectional views showing modifications; and Fig. 8 is a view corresponding to Fig. 1, 45 showing a modified construction of apparatus. Fig. 9 is a detail view.

In the construction shown in Figs. 1 to 5, inclusive, a and b are respectively the inlet and outlet expansion-tubes, rigidly fixed at 50 one end to the frame or body c of the trap, and d is the valve-case connecting the other or movable ends of the tubes, the arrangement being similar to that usually adopted in a Geipel steam-trap, except that the inlet- 55 tube a, which is preferably made of metal, such as brass, having a greater coefficient of expansion than the metal, preferably iron, of which the outlet-tube b is made, is arranged above the latter tube, so as to be nearest the 60 top of the trap-frame c. e is a water-discharge passage formed by a valve-seat e', screwed through an opening in the wall d' between the inlet and outlet chambers f and g. The passage e is controlled by a valve h, 65 which is located in the inlet-chamber f and

opens in a downward direction relatively to the valve-case d, the stem i of the valve extending through a stuffing-box k and bearing against the arm m of the hand-lever m m', it may be, as shown, through an endwise-adjustable screw n, the said lever being pivoted, as heretofore, to the trap-frame c at o. The inlet and outlet chambers f and g are connected, respectively, to the inlet and outlet pipes a and b. For this purpose the valve-case d is constructed, as shown more clearly in Figs. 2 to 5, inclusive, with a laterally-arranged downwardly-extending passage p, whereby the upper inlet branch q is placed in communication with the lower inlet-chamber 70 f, and with a laterally-arranged upwardly-extending passage r, whereby the lower outlet branch s is placed in communication with the upper outlet-chamber g.

With the arrangement described, when the 85 inlet-tube a contracts, owing to its becoming filled with water, its free end portion, together with the valve-case d and the free end portion of the tube b, will move upwardly, with the result that the valve-seat e' will 90 leave the valve h, which will be prevented from rising with the valve-case by reason of its stem i bearing against the arm m of the hand-lever m m' and permit water to pass 95 between the valve and its seat to the discharge-passage e, whereupon the valve h, owing to the pressure or wedging action of the accumulated and escaping water on its face, will be suddenly opened to its full extent in a downward direction and allow of 100 the rapid discharge of the water from the inlet-pipe a through the outlet-pipe b. When the tube a re-expands by reason of the water having been discharged therefrom and replaced by steam, the tubes and valve-case 105 will move in the opposite direction into their normal positions, and the valve will be caused by the rush of steam, aided, it may be, by a coiled spring p, to close against its seat e', upon which it will be held by the fluid-pressure 110 in the trap until the expansion-tube a is again filled with water and contracts to a sufficient extent to again cause the opening of the water-discharge passage e, whereupon the above-described operations will again 115 take place.

To prevent undue friction between the packing in the stuffing-box k and the valve-stem i, acting to retard the opening of the valve h upon contraction of the tube a, such 120 valve may be mounted loosely upon the inner end of the valve-stem, so that after being partly opened by the contraction of the tube a it can readily move inward into its fully-open position independently of the valve- 125 stem.

With the new arrangement of trap hereinbefore described it will be seen that the spring adjustment of the hand-lever described in my said former specification, the 130

object of which is to prevent overstraining of the trap by excessive pressures, is no longer necessary, because when the valve h is closed by the steam-pressure the movable parts a , b , and d of the trap, together with the valve, are free to move downward without constraint, so that any excessive steam-pressure will not cause the said movable parts to strain the valve, as would be the case in my 10 before-mentioned trap, if the spring adjustment were not provided. There is also the further difference between the new and the old arrangements of these steam-traps that in the new arrangement the arm m of the 15 hand-lever against which the valve acts is depressed to open the valve by hand to allow of water and steam blowing through the trap instead of being raised, as in the old arrangement.

20 The arm m' of the hand-lever $m m'$ may, if desired, rest against a fixed stop on the trap-frame c to limit its downward movement. In order, however, to utilize the upward movement of the tubes, due to contraction, to increase the extent of opening of the valve h it is preferred to cause one of the said tubes, preferably tube a , to act against the arm m' of the hand-lever through a rigid rod m^2 , resting on said tube, so that upward movement 25 of the tube will act to turn the lever on its fulcrum and push the valve h away from its seat e' at the time when the seat is moving away from the valve, and thereby increase the extent of opening for a given movement 30 of the tubes.

35 Fig. 6 shows the throttling device as used in the example illustrated for the purpose of automatically throttling the discharge of water for the purposes hereinbefore mentioned. 40 It comprises a flanged tube t , that is arranged to slide in the bush e^2 , Fig. 2, in which the seat e' and the discharge-passage e are formed, and is normally held against the outer end thereof by a spring t' , which is under compression and may conveniently be 45 held in place in the outlet-chamber g by a fixed extension t^2 therein. The force of the spring is such that normally and also when water is being discharged at low pressure the 50 throttling-tube t will be held in the fully-open position shown, in which the annular outlet-passage u between it and the extension t^2 is of its largest area; but when water is being discharged at high pressures the increased fluid 55 friction acting against the inner parts of the throttling-tube will force this tube outward against the action of the spring t' , so as to partially close the outlet-passage u to a greater or less extent, and so throttle the escape 60 of water and prevent chattering of the valve, vibration of the trap, and production of undue noise when the trap is discharging. The throttling device also serves, by reducing 65 the velocity of the water escaping past the valve-seat, to transfer the wear which or-

dinarily takes place during discharge, especially at high pressures, from the valve-seat e' to the sides of the discharge-opening u , where wear is of less consequence. The outer end of the throttling-tube t , as shown 70 in Fig. 6, is preferably notched or serrated or equivalently formed to prevent its ever completely closing the water-outlet opening under the greatest pressure to which the tube may be subjected, and there may be provided 75 in connection with such throttling-tube a renewable stop v in the form of a ring fixed to the extension t^2 , so that wear, due to the issuing water, can be readily compensated for. In some cases holes or passages t^3 may be provided 80 in the tube t under the flange, as shown.

A throttling device acting as described instead of being arranged in the valve-case d may be arranged in the outlet-tube b or in a water-discharge tube connected thereto and 85 extending beyond the trap. Fig. 7 shows one arrangement of this kind partly in elevation and partly in longitudinal section. The throttling device comprises a cone-valve w , controlling a water-passage w' in a wall or 90 partition w^2 in a valve-case w^3 , connecting two portions w^4 and w^5 of a water-discharge pipe, the winged stem w^6 of the valve extending through the passage w' and acting, through a plate w^7 , against a spring w^8 , that is 95 held in position by a stationary perforated plate w^9 . The arrangement is such that for low pressures the valve will be held fully open, so as to exert the minimum throttling effect; but for high pressures the valve will be partly 100 closed against the action of the spring w^8 , so as to exert its maximum throttling effect. It is, however, preferred to arrange the throttling device as in Figs. 1 and 2. Throttling devices constructed and operating as hereinbefore described can be used in expansion 105 steam-traps of various kinds.

I am aware that steam-traps have heretofore been provided with means for throttling the discharge of water therefrom; but the 110 throttling means employed have been such that there is no difference in the throttling action whether the pressure be high or low, so that if the throttling action is sufficient to prevent an undue discharge at high pressures then the discharge at low pressures has been too much throttled.

115 Instead of arranging the arm m' of the hand-lever to be operated by the expansion-tube a , as in Fig. 1, or arranging it to bear 120 against a fixed support, it may, as shown in Fig. 8, be arranged to bear (it may be through an adjustable screw x) against one arm 1 of a lever 125 1 2, pivoted at 3, and the other arm 2 of which acts through a pin 4 against the diaphragm 6 (or piston) of a controlling device comprising a casing 7, that is divided by the diaphragm into two chambers 8 and 9, the upper of which—viz., 8—is adapted to be placed in communication by a pipe 10 130

with the steam-pipe to which the tube *a* of the steam-trap is connected, so that the position of the arm *m* of the hand-lever *m m'*, against which the stem *i* of the valve *h* acts, 5 will be automatically varied upon variation in the steam-pressure to which the trap is subjected, as in steam-traps constructed according to British Letters Patent granted to me, No. 21,783 of 1897, the said arm *m* 10 moving upwardly when the steam-pressure falls below the normal and downwardly when the steam-pressure rises above the normal.

The valve *h* may sometimes, and as shown 15 in Fig. 9, be adapted to be rotated in an intermittent manner by providing it in a known way with vanes *h'*, against which the issuing water will act so as to turn the valve about its axis.

20 What I claim is—

1. An expansion steam-trap of the type herein referred to, comprising a frame or body, expansion-tubes rigidly fixed at one end to said frame or body and free to move 25 laterally at their outer ends, a valve-case connecting the free ends of said tubes and having inlet and outlet chambers connected by a water-discharge passage, a valve controlling said discharge-passage, and an external 30 abutment against which said valve can act through its spindle, said valve being arranged to open in an inward direction against the fluid-pressure within the trap when the expansion parts of the trap contract, and to close in an outward direction and to be held closed by the said fluid-pressure when the said parts again expand. 35

2. An expansion steam-trap of the type herein referred to comprising a frame or body, inlet and outlet expansion-tubes fixed at one end to said frame or body, a valve-case fixed to the free ends of said tubes, having inlet and outlet chambers that are connected respectively to the inlet and outlet tubes, and 40 are directly connected together by a water-discharge passage, a valve controlling said discharge-passage, and an external abutment against which said valve can act through its spindle, said abutment being carried by 45 that part of the frame or body to which the inlet expansion-tube is nearest and toward which said tube moves when it contracts, said valve being arranged to open in an inward direction against the fluid-pressure within the trap when the expansion parts of 50 the trap contract, and to close in an outward direction and to be held closed by the said fluid-pressure when the said parts again expand. 55

60 3. An expansion steam-trap of the type herein referred to comprising a frame or body, an upper inlet expansion-tube and a lower outlet expansion-tube fixed to said frame or body, a valve-case fixed to the free 65 ends of said tubes and having upper and

lower chambers to the lower of which the inlet expansion-tube is connected and to the upper of which the outlet expansion-tube is connected, a water-discharge passage connecting said upper and lower chambers, a 70 valve arranged in the lower chamber to control said discharge-passage and provided with a spindle extending to the exterior of said valve-case, and an external abutment against which said valve can act through its spindle, 75 said valve being arranged to open in an inward direction against the fluid-pressure within the trap when the expansion parts of the trap contract, and to close in an outward direction and to be held closed by the said fluid-pressure when the said parts again expand. 80

4. An expansion steam-trap of the type herein referred to comprising a frame or body, an upper inlet expansion-tube and a 85 lower outlet expansion-tube fixed to said frame or body, a valve-case fixed to the free ends of said tubes and having upper and lower chambers to the lower of which the inlet expansion-tube is connected and to the upper 90 of which the outlet expansion-tube is connected, a water-discharge passage connecting said upper and lower chambers, a valve controlling said discharge-passage, said valve being arranged to open in an inward direction against the fluid-pressure within the trap when the expansion parts of the trap contract, and to close in an outward direction and to be held closed by the said fluid-pressure when the said parts again expand, 95 and means for controlling and operating said valve. 100

5. An expansion steam-trap of the type herein referred to comprising a frame or body, an upper inlet expansion-tube and a 105 lower outlet expansion-tube fixed to said frame or body, a valve-case fixed to the free ends of said tubes and having upper and lower chambers to the lower of which the inlet expansion-tube is connected and to the 110 upper of which the outlet expansion-tube is connected, a water-discharge passage connecting said upper and lower chambers, a valve controlling said discharge-passage and arranged in the lower chamber of the valve-case so as to open in a downward and inward direction and to close in an upward and outward direction, and means for controlling and operating said valve. 115

6. In combination with an expansion 120 steam-trap having a discharge-valve, an automatic throttling device arranged in the water-discharge passage of said trap at the outer side of the water-discharge valve and capable of being moved to different extents 125 according to the pressure of the escaping water, said throttling device being adapted to oppose a yielding resistance to the water-pressure and to produce a variable throttling action according to its extent of movement. 130

7. In combination with an expansion steam-trap, having a discharge-valve, an automatic throttling device arranged in the water-discharge passage of said trap at the outer side of the water-discharge valve and in the path of escaping water, and a spring that normally holds the said throttling device in its open position and permits the same to close the passage to a greater or less extent according to the pressure upon it of the escaping water.

8. An expansion steam-trap of the type herein referred to comprising a frame or body, inlet and outlet expansion-tubes fixed at one end to said frame or body, a valve-case fixed to the free ends of said tubes and having inlet and outlet chambers that are connected respectively to the inlet and outlet tubes and are directly connected together by a water-discharge passage, a valve controlling said discharge-passage, said valve being arranged to open in an inward direction against the fluid-pressure within the trap when the expansion parts of the trap contract, and to close in an outward direction and to be held closed by the said fluid-pressure when the said parts again expand, and an automatic throttling device arranged in the water-discharge passage of said trap so as to be operated by the pressure of escaping water after the same has passed the water-discharge valve of the trap, said throttling device being adapted to offer a variable throttling action according to the pressure of the escaping water.

9. An expansion steam-trap of the type herein referred to, comprising a frame or body, expansion-tubes rigidly fixed at one end to said frame or body and free to move laterally at their outer ends, a valve-case connecting the free ends of said tubes and having inlet and outlet chambers connected by a water-discharge passage, a valve controlling said water-discharge passage, means for operating and controlling said valve, and an automatic throttling device arranged at the exit side of said valve and whereby at low pressures a maximum opening for escaping water is produced, and at high pressures a minimum opening is produced.

10. An expansion steam-trap of the type herein referred to comprising a frame or body, an upper expansion-tube and a lower outlet expansion-tube fixed to said frame or body, a valve-case fixed to the free ends of said tubes and having upper and lower chambers to the lower of which the inlet expansion-tube is connected and to the upper of which the outlet expansion-tube is connected, a water-discharge passage connecting said upper and lower chambers, a valve controlling said water-discharge passage, means for operating and controlling said valve, and an automatic throttling device arranged at the exit side of said valve and whereby at

low pressures a maximum opening for escaping water is produced, and at high pressures a minimum opening is produced.

11. An expansion steam-trap of the type herein referred to, comprising a frame or body, expansion-tubes rigidly fixed at one end to said frame or body and free to move laterally at their outer ends, a valve-case connecting the free ends of said tubes and having inlet and outlet chambers connected by a water-discharge passage, a valve controlling said discharge-passage, means for operating and controlling said valve, an automatic throttling-valve, and a spring controlling said throttling-valve so that at low pressures a maximum opening for escaping water or steam will be produced, and at high pressures a minimum opening will be produced.

12. An expansion steam-trap of the type herein referred to comprising a frame or body, inlet and outlet expansion-tubes fixed at one end to said frame or body, a valve-case fixed to the free ends of said tubes and having inlet and outlet chambers that are connected respectively to the inlet and outlet tubes and are directly connected together by a water-discharge passage, an inwardly-opening valve controlling said discharge-passage, means for operating and controlling said valve, an automatic throttling-valve, and a spring controlling said throttling-valve so that at low pressures a maximum opening for escaping water or steam will be produced, and at high pressures a minimum opening will be produced.

13. An expansion steam-trap of the type herein referred to comprising a frame or body, an upper inlet expansion-tube and a lower outlet expansion-tube fixed to said frame or body, a valve-case fixed to the free ends of said tubes and having upper and lower chambers to the lower of which the inlet expansion-tube is connected and to the upper of which the outlet expansion-tube is connected, a water-discharge passage connecting said upper and lower chambers, a valve arranged in the lower chamber to control said discharge-passage and provided with a spindle extending to the exterior of said valve-case, and an external abutment against which said valve can act through its spindle, said valve being arranged to open in an inward direction against the fluid-pressure within the trap when the expansion parts of the trap contract, and to close in an outward direction and to be held closed by the said fluid-pressure when the said parts again expand, said valve being also mounted to slide endwise upon its spindle so that upon being opened to a small extent by the contraction of parts of the trap it will be free to be quickly moved into its fully-open position by the issuing water independently of the said spindle.

14. An expansion steam-trap of the type

- herein referred to comprising a frame or body, an upper inlet expansion-tube and a lower outlet expansion-tube fixed to said frame or body, a valve-case fixed to the free ends of 5 said tubes and having upper and lower chambers to the lower of which the inlet expansion-tube is connected and to the upper of which the outlet expansion-tube is connected, a water-discharge passage connecting said upper and lower chambers, a valve 10 controlling said discharge-passage and provided with a spindle extending to the exterior of said valve-case, arranged to open in an inward direction against the fluid-pressure within the trap when the expansion parts of the trap contract, and to close in an outward direction and to be held closed by the said 15 fluid-pressure when the said parts again expand, and a lever mounted on the 20 trap-frame and against one arm of which the said valve-spindle can bear when the trap contracts.

15. An expansion steam-trap of the type herein referred to comprising a frame or body, 25 an upper inlet expansion-tube and a lower outlet expansion-tube fixed to said frame or body, a valve-case fixed to the free ends of

30 said tubes and having upper and lower chambers to the lower of which the inlet expansion-tube is connected and to the upper of which the outlet expansion-tube is connected, a water-discharge passage connecting said upper and lower chambers, a valve 35 controlling said discharge-passage and provided with a spindle extending to the exterior of said valve-case, arranged to open in an inward direction against the fluid-pressure within the trap when the expansion parts of the trap contract, and to close in an outward direction and to be held closed by the said 40 fluid-pressure when the said parts again expand, and a lever mounted on the trap-frame and against one arm of which the said valve-spindle can bear when the trap contracts and the other arm of which has connected to it a thrust-rod that bears against 45 one of the expansion-tubes.

Signed at London, England, this 29th day of June, 1906.
